(57) **CLAIM**

An ornamental design for a door chime with illumination, as shown and described.

DESCRIPTION

The patent or application file contains at least one drawing executed in color. Copies of this patent or patent application publication with color drawing(s) will be provided by the Office upon request and payment of the necessary fee. **862**
FIG. 1 is a perspective view of a door chime with illumination present as represented by the stippling in the drawing; FIG. 2 is a front elevation view of the door chime of FIG. 1;

FIGS. 3-6 are left, right, top and bottom views of the door chime of FIG. 1;

FIG. 7 is a perspective view of the door chime without illumination present;

FIG. 8 is a front elevation view of the door chime of FIG. 7;

FIGS. 9-12 are left, right, top and bottom views of the door chime of FIG. 7;

FIG. 13 is a perspective view of an embodiment of the door chime of FIG. 1 with illumination present, wherein the illumination is blue in color;

FIG. 14 is a perspective view of an embodiment of the door chime of FIG. 1 with illumination present, wherein the illumination is cyan in color;

FIG. 15 is a perspective view of an embodiment of the door chime of FIG. 1 with illumination present, wherein the illumination is green in color;

FIG. 16 is a perspective view of an embodiment of the door chime of FIG. 1 with illumination present, wherein the illumination is magenta in color;

FIG. 17 is a perspective view of an embodiment of the door chime of FIG. 1 with illumination present, wherein the illumination is red in color;

FIG. 18 is a perspective view of an embodiment of the door chime of FIG. 1 with illumination present, wherein the illumination is white in color; and,

FIG. 19 is a perspective view of an embodiment of the door chime of FIG. 1 with illumination present, wherein the illumination is yellow in color.
